UNITED STATES PATENT OFFICE.

CHESTER B. MILLS, OF BROOKLYN, NEW YORK, ASSIGNOR TO SPERRY GYROSCOPE COMPANY, OF BROOKLYN, NEW YORK, A CORPORATION OF NEW YORK.

SEARCHLIGHT.

Application filed August 26, 1922. Serial No. 584,399.

This invention relates to high-intensity searchlights designed particularly for use upon small naval craft such as destroyers and submersible craft. It has been found impracticable to utilize the standard naval type of searchlight on submersible craft, since this involved the necessity of providing a water-tight hatch into which said searchlight could be lowered for protection.

10 It is one object of this invention to provide a searchlight having a water-tight drum, thus obviating the necessity for a water-tight hatch.

It is a further object of this invention to provide a searchlight drum capable of withstanding the water pressures met with in ordinary diving and maneuvering.

20 A further object is the provision of means for automatically preventing the collapse of the said drum under pressures greater than those met with in ordinary diving and maneuvering.

25 A further object is the provision of a searchlight mounting whereby the searchlight may be quickly operated to effective or ineffective position.

30 A further object of this invention is the provision of a water-tight searchlight drum having communication with the atmosphere only through a ventilation passage, and having means for rapidly closing or opening said passage.

35 A further object is the provision of a lamp which is inexpensive, of simple construction, light in weight, and of high efficiency, said searchlight comprising cast metal parts. This construction permits a standard searchlight, such as the Sperry high-intensity lamp, to be mounted on craft such as destroyers. 40 Their use upon such craft was hitherto prevented because their great weight on the necessarily elevated towers materially lowered the metacentric height of the craft and induced severe rolling and instability even under ordinary sea conditions. The cast metal parts permit a light material, such as an aluminum alloy, to be used, and also obviate the use of a great many connecting members, such as bolts, screws and the like, which ordinarily materially increase the 45 weight of the lamp.

50 Other objects and advantages will be in part obvious and in part specifically pointed out in the specification.

55 In the accompanying drawings

Fig. 1 is side view, partly sectioned vertically, of a high-intensity searchlight mounted on the deck of a submersible vessel.

Fig. 2 is a front view of the ventilating inlet and outlet passages, showing a portion 60 of the cover-lock construction.

Fig. 3 is a vertical section through a portion of the ventilating system.

Fig. 4 is a vertical section showing a modified mounting of the cover for the ventilating inlet and outlet passages. 65

Fig. 5 is a front elevation of a second form of high-intensity searchlight.

Fig. 6 is a side elevation of the searchlight shown in Fig. 5. 70

Fig. 7 is a vertical section through the drum of the searchlight shown in Figs. 5 and 6.

Fig. 8 is a vertical section showing a portion of the ventilating system. 75

Fig. 9 is an inner view of the cover showing the ventilating ports.

Fig. 10 is a vertical section through the cover.

Fig. 11 is a section taken through one of 80 the ventilating passages in the cover.

Fig. 12 is a vertical section through the upper portion of the searchlight drum.

Fig. 13 is an enlarged view, partly sectioned vertically, of the end of the compressed air tank having an automatic valve attached thereto. 85

Fig. 14 is a vertical section through a portion of the searchlight drum and an automatic valve applied thereto. 90

Referring to Figs. 1 to 4 inclusive, there is shown a high-intensity searchlight which comprises a drum having a cast-metal, jointless main body or barrel 10, a lens or glass window 11 at the front curved outwardly to withstand greater pressure, and a mirror 12 (see Fig. 3) protected by a cover 13 spaced therefrom at the rear. Said cover and barrel may be provided with cooperating flanges 14 and 15, respectively, whereby said cover may be attached to said barrel, as by thumb-screws 16. A washer is interposed between the flanges to render the joint watertight. Both the transparent window and the mirror are set in gaskets, such as 17 in Fig. 3 to form water-tight joints. Cast preferably integral with the body 10 is a housing 20 divided by a partition 21 to form two passages 22 and 23, the former communicating with a passage leading from the fan or 110

other air-current-producing device 25 in said housing, and the latter communicating with the space between mirror 12 and cover 13. By this arrangement a current of air is blown out from the interior of the lamp to the outside through passage 22, said air being replaced by a cool current entering through passage 23 and flowing between the mirror 12 and the cover 13 through a plurality of distributing ports 30 in the lower portion of the cover (see Fig. 8) and thence into the body of the lamp.

It will be apparent from the foregoing description that the drum has but one source of communication with the exterior, i. e., through the opening in housing 20, but is otherwise absolutely water-tight. When the drum is to be submerged, the opening in housing 20 leading to the outlet and inlet passages 22 and 23 may be closed by a cover or cap applied to said opening in any suitable manner to form a water-tight closure. As shown, housing 20 is provided adjacent said opening with a plurality of spaced segmental flanges 32, said flanges being in the form of cams or screw threads. The cap 35 is provided with grooved projections 36 also in the form of cams or screw threads adapted to be inserted in the spaces between flanges 32 and then, by approximately a quarter turn, engage over the flanges. The construction is similar to that used in breech-blocks. For easy handling, the cap may be provided with handles 37, and to prevent its detachment from the drum a chain 38 may be fixed at one end to the cap and at the other end to the drum or housing. The usual washer 29 may be interposed between the cap and the open end of the housing 20.

40 A modified mounting for the cap is illustrated in Fig. 4. In this construction the cap is slidable toward or away from the opening upon a rod 40 threaded at one end into the partition 21 and extending through a central hub 41 in the cap. Means, such as a spring detent 42, may be provided to hold the cap in outward position when the light, and hence the ventilating system, is in operation.

50 The application of the water-tight drum, as hereinafter described, to a submarine vessel, is illustrated in Fig. 1, wherein the main deck of said vessel is indicated at 50 and the inner, water-tight deck is indicated at 51. The drum may be pivoted in trunnions 52 fixed upon a post or support 53 extending through an opening 55 in the main deck 50 and pivoted in a bracket 54 fixed to the deck 51. The opening 55 is large enough to permit the post and lamp to be swung from elevated or effective position (as shown by the full lines) to lowered or ineffective position (as shown by the dotted lines) below the main deck. The raising and lowering operations may be facilitated by a dashpot

56, pivoted at one end upon a bracket 57 fixed to the deck 51 and in which operates a piston 58 connected by a link 59 to the lower end of post 53. Within the dash-pot is positioned a spring 60 normally tending to force piston 58 to the outer end of the dash-pot and raise the lamp.

Without providing any water-tight compartments, it is apparent that the lamp may be safely and rapidly stored below the main deck. The searchlight drum being water-tight, filling of the space between decks 50 and 51 with water will not affect the lamp. The drum is constructed of non-corrosive, preferably light material, such as an aluminum alloy. The electric connections may extend through post 53 and one of the trunnions 52 to the lamp. The drum may be raised or lowered about its pivots by means of a hand-wheel 62, and may be held in position by a set-screw 63 operating in a slot 64 in wheel 62.

The drum is constructed to withstand any desired external water pressure without leaking, e. g., a pressure equivalent to a hydraulic head of 75 ft., beyond which the searchlight will seldom be carried in ordinary diving or maneuvering of a submersible craft. Means may be provided however, which permit submersion beyond the calculated safe depth without injury to the lamp. For this purpose, there may be provided in the stowing quarters between decks 50 and 51 a tank 65 carrying air under pressure and connected to the interior of the searchlight drum, as by a metallic hose 66. The tank may be provided with some well-known form of valve, such as a diaphragm valve, adapted to discharge automatically, when the predetermined safe depth of submergence (75 ft., say,) is exceeded, a sufficient quantity of air into the drum so that the difference of pressure between the outside and inside of the drum does not exceed the predetermined safe pressure. This valve may 100 take the form shown in Fig. 13 and comprises a chamber 101 fixed in any suitable manner to the compressed air tank and having a passage 102 communicating with the interior of the tank. Said passage is normally closed by a valve 103 at one end of a valve stem 104, the other end of which is fixed to a diaphragm 105, which divides chamber 101 into two compartments 106 and 107. A spring 108 pressing at one end against a fixed shoulder 109 and connected at its other end to the valve stem normally presses the diaphragm outwardly and closes the valve against its seat 110. The compartment 107 is in communication with the outside by a plurality of openings 111, while the compartment 106 is in communication with the interior of the searchlight drum by cable 66. It will be apparent that the tension of spring 108 may be such that when the 115

searchlight is submerged to a point where the pressure outside the searchlight exceeds by a predetermined amount the pressure inside thereof, the pressure of the sea water upon the diaphragm will unseat valve 103 and permit compressed air to enter the drum and reduce the pressure differential. The tension of spring 108 may be varied by means of nut 112 threaded upon the end of stem 104 and abutting against valve 103.

The drum may be provided with a similar valve so that when the vessel rises to the surface the excess pressure therein may be automatically relieved. For this purpose, there may be provided the valve illustrated in Fig. 14. Said valve operates in a housing formed by a plate 120 having an inner threaded flange 121 co-operating with a threaded opening cut in the drum 64, and having an outer threaded flange 122 on which is threaded a casing 123. Plate 120 is provided with a substantially central boss 125 provided with a plurality of bores 124. Through the central bore operates a valve stem 126 having a valve 127 at its upper end cooperating with the bores. A spring 128 abuts at one end against the inner surface of hub 125 and at the other end against a flanged disc 130, threaded on the end of the valve stem and adjusted in position by lock-nuts 131 to vary the tension of spring 128. The spring thus normally holds the valve in closed position. The casing 123 is provided with a plurality of openings 135 to permit communication between the interior and the exterior thereof. It will be obvious that when the outside pressure falls sufficiently, the pressure within drum 64 operating on the valve through bores 124 will overcome the tension of the spring and unseat the valve, thus allowing a reduction of the internal pressure. It will be understood that the valve structure hereinbefore described is merely illustrative of the principle involved, but that other well-known types of valves may be substituted therefor.

In Figs. 5-12 there is illustrated a second form of searchlight suitable for use upon destroyers and other light, swift craft. One of the main considerations in searchlights of this type is that of weight which must be reduced to a minimum in order not to lower the metacentric height of the craft and render it unstable. At the same time it is desirable to obtain as powerful a light as possible, which necessitates utilizing searchlights in excess of the 24" type and of correspondingly great weight. To permit the use of large lamps upon light craft this invention provides a construction whereby the weight of said lamps is materially reduced. For this purpose the lamp comprises a drum 70 pivotally mounted in trunnions 71 of a member 72 rotatably mounted on a base 73.

65 The drum comprises a main casing or barrel

portion 75, a cover 76, and a ventilation housing or casing 77. All of these portions comprising the drum, as well as the trunnion member 72 and the base 73 are in the form of castings made of a light metal such as 70 an aluminum alloy. The barrel 75 is formed integral with the container 78 for the usual control mechanism including a switch which may be operated from the outside by a handle 79. The barrel is preferably formed 75 complete for the reception of the front window at the front and with means for attaching the mirror cover at the rear. At the front an inwardly projecting annular flange 75' is shown as cast integrally with 80 the barrel forming a face for the reception of the front window as hereinafter described. At the back the barrel is formed with an outwardly projecting annular flange 175 and with an integrally cast ear 176 for the reception and hinging of the back 76 of the mirror. The casing 77 may be bolted to the top of barrel 75, and the cover 76 may be pivoted to the rear of said barrel and locked by latches 80. Various openings may 90 be provided in the main casing or barrel to allow access to various parts of the lamp mechanism, and are normally closed by covers 81, 82, 83, 84 which are held in position by any suitable fastening means. The 95 barrel is provided at the front with a window 85 (see Fig. 12) set in a gasket 86, and with a signaling shutter 87 operated by a handle 88 from outside the barrel, as is more fully disclosed in the application of 100 Theodore Hall, Ser. No. 211,288, filed Jan. 10, 1918. At the rear of the barrel there is mounted the mirror 89 set in a gasket 86.

The cover 76 is spaced from mirror 89 and is provided with a cut-out portion near 105 its top forming a passage 90 from the outside. The entrance to said passage is protected by an overhanging portion or guard 92 integral with the cover. Air enters passage 90, passes down between the cover and the mirror, through a plurality of openings 110 30 (see Figs. 8 and 9) upwardly along the front of the mirror to replace the air forced out of the lamp by the ventilating blower 93 operated by motor 94 within the casing 115 77. The blower drives air from the interior of the lamp through passage 95 to the exterior by way of passage 96 (see Fig. 5). The casing 77 may be spaced from barrel 75 along its lower edges as at 97 to permit 120 any collected moisture within casing 77 to drain.

The drum may be rotated in its bearings by a hand-wheel 62 and fixed in position by a set-screw 64 operating in slot 63, as hereinbefore described. The usual scale 98 may be provided on the base 73 cooperating with a pointer 99 on member 72, the latter being provided with the usual reading lamp 100.

125 65 In accordance with the provisions of the 130

patent statutes, I have herein described the principle of operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

15 Having described my invention, what I claim and desire to secure by Letters Patent is:

1. A searchlight drum comprising a cast-metal body having a laterally projecting housing formed integral therewith, said

body having an opening, and a cast-metal cover for closing said opening.

2. A cast aluminum alloy searchlight drum comprising a body having a laterally projecting housing formed integral therewith, said body having front and rear openings, a cast aluminum alloy cover for sealing said rear opening, and a glass window for sealing said front opening.

3. A cast metal searchlight drum comprising a body having a ventilation housing formed integral therewith, said body having front and rear openings, a cover for sealing said rear opening, said ventilation housing having an opening, and a detachable cover for sealing said last-named opening.

In testimony whereof I have affixed my signature.

CHESTER B. MILLS.
